UNITED STATES PATENT OFFICE.

BERNHARD BALG, OF GÖRLITZ, GERMANY.

APPARATUS FOR PRODUCING HOLLOW ARTICLES.

1,205,839.

Specification of Letters Patent. Patented Nov. 21, 1916.

Original application filed August 17, 1909, Serial No. 513,281. Divided and this application filed November 15, 1911. Serial No. 660,432.

To all whom it may concern:

Be it known that I, BERNHARD BALG, manufacturer, a subject of the King of Prussia, residing at 20 Postplatz, in the city of Görlitz, Silesia, in the Kingdom of Prussia and Empire of Germany, have invented new and useful Improvements in Apparatus for Producing Hollow Articles, of which the following is a specification.

10 For a long time attempts have been made to produce in a simple manner, hollow articles, such as building blocks closed on all sides. This problem has now been solved according to the present invention, by causing a stream of plastic material to issue from a press in a stream composed of a series of alternately succeeding internally hollow portions and intervening webs, so that it is merely necessary to divide the said 20 stream transversely, in order to produce a hollow building block in one operation.

The formation of the series of alternately succeeding hollow portions and intervening webs may be effected in various ways, for 25 instance by employing a core for making the hollow portions, the core being disposed in the mouth piece of the press for forming the hollow portion and removed therefrom when the web is being formed.

30 In the accompanying drawings: Figure 1 is a diagrammatic longitudinal section of the stream of plastic material as it issues from the press. Fig. 2 is a vertical longitudinal section, and Fig. 3 is a vertical cross section through the mouthpiece of a press. Figs. 4 and 5 are, respectively, a vertical longitudinal section and a vertical cross section of a modification; and Figs. 6 and 7 are corresponding views of a second modification.

40 One or more cores 6 according to the desired number of internal cavities which the blocks are to have in the transverse direction are arranged in the mouthpiece 7 of the press. These cores which may have any desired shape and cross section are capable of being rendered active or inactive alternatively according to my invention. This may be effected in various ways, three arrangements for this purpose being illustrated in Figs. 2 to 7.

In the construction shown in Figs. 2 and 3, the core 6 is carried by a rod 8, extending transversely through the press head 9.

On one end of this rod, externally of the press head, there is mounted (with some play) the hand lever 10, which is fixed on a shaft 11, that is mounted below the press head and is capable of rocking in its bearing. On the opposite end of the shaft 11 there is fixed a second lever 12, which is also arranged to act upon the rod 8 with a slight amount of play. On moving the hand lever 10 the rod 8 is consequently moved, together with the core 6 uniformly in either direction.

The core 6 projects into the mouthpiece 7 of the press and is guided with a tight joint in a closed casing 13 which is formed in each side with a slot for the passage of the rod 8. The rod 8 is likewise guided either in lateral extensions of the casing 13 or in a separate casing (Fig. 3). The casing 13 is fitted with a pipe 14, which serves for conveying water or oil and for the escape or the admission of air.

The core 6 is (see Fig. 2) provided, in front, with one or more pins 15, which are pointed conically at their ends and serve to form air holes in the webs or solid portions 80 of building blocks or other articles. These pins may have any desired cross section.

In the construction shown in Figs. 4 and 5, the core 6 is provided with a rack 16 with which engages a pinion mounted on a shaft 85 17. On the outer end of this shaft 17 is a crank 18 by means of which the core can be moved back and forth. The rack and the pinion are inclosed in a casing 19, in which the core 6 is guided with a tight joint. 90

In the construction shown in Figs. 6 and 7 the core 6 is mounted so as to be capable of rotating with an axle 20 on the end of which, situated outside the presshead, is a crank handle 21. By turning this crank 95 handle, in the direction of the arrows shown in Fig. 6, the core can be turned back into the position shown in dotted lines (to permit the stream to unite) and also forward again into the working position, or that 100 shown in full lines, to compel the plastic material to issue in tubular form from the mouthpiece 7.

In the constructions shown in Figs. 2 to 7 the forming of the solid portions in the 105 stream of plastic material issuing from the press is effected by removing or putting in and out the core or cores temporarily.

When the cores are moved back—drawn from the mouthpiece—the great pressure exerted by the press produces a web in the issuing stream. After the cores have been moved forward again, the plastic material continues to issue as a hollow stream. The stream is separated, transversely, in the usual manner, into its several portions by means of any usual cutting devices through 10 the solid portions 3 and 4 (Fig. 1). The cutting devices may be connected to the lever 10, 18 or 21 in such a manner that when they are operated they also cause the said lever to operate.

15 The stream may be divided at any points. Thus, as shown in Fig. 1, the cuts may be made (at 3, 4) through the webs 2 to produce hollow building or other blocks closed on all sides; and, when it is desired, that the 20 blocks shall have very thin end walls, the separation of the stream, may be effected by means of two wires stretched apart side by side as indicated at 5. The cuts may be made instead or also at the thinner parts 25 of the stream, to produce pots or other hollow articles. It will also be understood, that the cuts may be made at such points that the product will have a succession of hollow spaces and webs.

30 It is an essential feature of my apparatus that it shall have means whereby the outlet area of the exit mouthpiece may be varied, at desired intervals of time, in order that the plastic material (which normally issues 35 in tubular form from the mouthpiece) may be manipulated in any manner, to the end that, at said intervals, the plastic material forms webs in or ends of hollow blocks or other hollow articles.

40 Pins (such as 15) are so mounted, in any suitable manner, as to be capable of movement in the mouthpiece. When the cores are provided with these pins 15 the latter pierce the previously - formed solid portion 45 of the stream from behind and thus, as before outlined, form air holes in the abutting ends of the two adjacent hollow blocks that are subsequently separated from each other.

The improved apparatus is applicable to 50 the production of all kinds of building or other blocks closed on all sides, or other hol-

low articles, from any plastic material and the said blocks may be formed with one or more internal cavities by employing the corresponding number of cores.

55 The present application is a division of an application, Serial No. 513281, filed August 17, 1909 and the process which is herein mentioned, constitutes the subject-matter of a divisional application, Serial No. 567629, filed June 18, 1910.

What I claim is:

1. In an apparatus for producing hollow articles, the combination of an exit mouthpiece and a core therein, the mouthpiece and core being relatively movable from a position in which the core is within the mouthpiece to a position in which the core is behind the mouthpiece, a press for forcing plastic material to issue from the mouthpiece, and means for changing the relation of the core and mouthpiece from one relative position to the other, said core when it is within the mouthpiece being adapted to direct the material to issue in tubular 75 form, while when the core is behind the mouthpiece the material may issue in solid form, when webs may be formed in the hollow articles.

80 2. In an apparatus for producing hollow articles, the combination of, a press having a mouth piece; and a core for causing plastic material to issue therefrom in a tubular stream, said core being capable of being moved to an inactive position temporarily 85 for forming an intervening web.

3. In an apparatus for producing hollow articles, the combination, of a press having a mouth piece; a core for causing plastic material to issue therefrom in a tubular 90 stream, said core being capable of being moved to an inactive position temporarily for forming an intervening web, and a pin 95 on said core for forming openings in said web.

In testimony whereof I have signed my name to this specification in the presence of two subscribing witnesses.

BERNHARD BALG.
